UNITED STATES PATENT OFFICE.

JOHN L. DAY, OF MEMPHIS, TENNESSEE.

AUTOMOBILE-LAMP.

1,101,122.

Specification of Letters Patent. Patented June 23, 1914.

Application filed January 12, 1914. Serial No. 811,578.

To all whom it may concern:

Be it known that I, JOHN L. DAY, a citizen of the United States of America, residing at Memphis, in the county of Shelby and State of Tennessee, have invented certain new and useful Improvements in Automobile-Lamps, of which the following is a specification.

My present invention relates to improvements in automobile lamps, and is designed particularly with a view to simplifying automobile lights in certain details.

In many rear or tail lights for automobiles as at present in use, the lamps are complicated in construction, are difficult in manipulation, comparatively expensive in cost of production due to their numerous parts, and the glass which invariably incloses the lamp, quickly becomes coated with dust and constantly requires attention to prevent the consequent dimming and loss of effectiveness of the lamp.

By the utilization of my invention I provide a lamp which combines a red light or danger signal in connection with the tail lamp for illuminating the number or license plate of the automobile; which is compact and simple in construction, facile in its manipulation and accessibility, efficient, and economical.

The invention consists in certain novel features of construction and combinations and arrangements of parts as hereinafter set forth and claimed.

In the accompanying drawings I have illustrated one complete example of the physical embodiment of my invention constructed according to the best mode I have so far devised for the practical application of the principles of the invention.

Figure 1 is an elevation of the device complete, ready for attachment to an automobile. Fig. 2 is an end view of Fig. 1 looking from the right. Fig. 3 is a bottom plan view of Fig. 2. Fig. 4 is an enlarged, detail view, partly broken away, showing the manner of supporting the lamp as indicated in dotted lines Fig. 3.

In the preferred embodiment of my invention I have illustrated an electric lamp as the illuminating medium inclosed within the hood or casing 1. The hood is preferably of sheet metal, nickel plated on its exterior for ornamentation, and either enameled or painted white on the interior for the purpose of reflecting the rays of light from

the lamp. As best seen in Fig. 2 the hood or casing is semi-circular in cross section or concavo-convex, and in Fig. 3 the open bottom of the hood is illustrated as bounded by the horizontal flange 2 to which the screen 3 of foraminous material is secured at three sides. The fourth side of the screen is secured in the bent back wall 4 of the hood which projects below the hood proper throughout its entire length. A cylindrical barrel 5, integral with the hood projects therefrom, and is provided with a lens 6 preferably red for a danger signal, and in Fig. 1 it is seen that the barrel is centrally located with relation to the hood, facing the rear. In addition to holding the screen, the bent back wall 4 of the hood, also performs the function of an attaching device for the number or tag plate 7 bearing the license number of the automobile upon which it is used. This license or number plate is secured between the back wall 4 and a base plate 8 by bolts or screws 9, and this base plate is in turn adapted to be attached to a part of the automobile in the customary manner.

The lamp bulb 10 which provides the illumination of the device is introduced into and retained in the hood in a novel and especially meritorious manner. The end wall 11 of the hood is provided with an orifice of suitable size and this orifice is bounded and its walls strengthened by a cast ring 12 formed with a threaded flange 13 projecting inwardly from the hood wall 11. It will be noted that the inside diameter of the flanged ring or plate 12 is of sufficient size to permit the entrance of the lamp bulb 10, and this flanged ring is adapted to receive a threaded ferrule or hollow plug 14 having a knurled turning handle or head 15 at the outer side of the hood and a reduced stem 16 projecting inside the hood. The stem 16 is for the attachment of a pipe 17 which is threaded on the stem and on the electric lamp bulb 10. The wires 18 are introduced through the opening in the ferrule and stem, thence through the pipe 17 to the lamp where they are attached in customary manner.

From this description it will be seen that the lamp may be removed, bodily, from the hood, by turning the handle or head 15 to unscrew the ferrule from the threaded flanged ring, and the lamp may be introduced and retained in the hood by screwing up the head as will be understood. The pipe

17 is of a length suitable to bring the lamp bulb directly behind the lens or red glass 6 as seen in Fig. 1, and its central location permits an equal distribution of the light rays, direct, and by reflection from the walls of the hood upon the license number plate.

Especial attention is called to the merits of the foraminous screen which protects the lamp from all extraneous dangers, eliminates the possibility of dust settling between the lamp and number plate, and yet does not interfere with the rays of light shed from the lamp.

15 From the above description taken in connection with my drawings it is evident that I have provided an automobile lamp which

fulfils the purposes and objects set forth to be accomplished by my invention.

What I claim is:—

In an automobile lamp, the combination with an open bottom screened hood having a flange threaded ring attached at the inner side of one of its end walls, a threaded open plug screwed into said ring, a threaded stem 20 projecting from the plug, a threaded pipe 25 screwed on the plug, and a lamp supported in the pipe as described.

In testimony whereof I affix my signature in presence of two witnesses.

JOHN L. DAY.
